HYDRAULIC DRILLING DEVICE

Eugen Merten, Houston, Tex., assignor to Shell
Development Company, San Francisco, Calif.,
a corporation of Delaware

Application September 27, 1940, Serial No. 358,585

4 Claims. (Cl. 255—24)

This invention relates to hydraulically operated drilling devices, and pertains more particularly to a system wherein high pressures generated by the so-called water-hammer effect are utilized for drilling purposes.

Although rotary methods have heretofore been commonly applied for the drilling of deep wells, it has now been found that superior results may be obtained by impact drilling or by a combination of impact with rotary drilling. This is especially true in drilling through extremely hard rock formations and in drilling relatively shallow boreholes, such as are used in seismic exploration, geochemical prospecting, etc.

It is, therefore, an object of this invention to provide a system wherein water-hammer effects or impulses are utilized for impacting a drill bit against earth formations.

It is also an object of this invention to provide a drilling system comprising a valve capable of suddenly stopping the fluid flow in a conduit to generate high pressure water-hammer effects.

It is also an object of this invention to provide a system wherein water-hammer impact drilling is combined with rotary drilling to secure optimum penetration effects.

It is also an object of this invention to provide a hydraulic impact drilling system comprising flow equalizers for controlling the frequency of the bit impacts and for absorbing shocks and minimizing the shattering effects of water-hammer pressures on the equipment.

It is also an object of this invention to provide a system whereby hydraulic impact drilling may be carried out with relatively small quantities of water.

These and other objects of the present invention will be understood from the following description with reference to the attached drawing, wherein:

Fig. 1 is a diagrammatic vertical cross-section view showing an embodiment of the impact bit and valve of the present invention, together with the supporting tubing, flow equalizers, and tubing head equipment;

Fig. 2 is a diagrammatic cross-section view of another embodiment of an inside flow equalizer or shock absorber; and

Fig. 3 shows diagrammatically a valve which may be used in the bit of Fig. 1.

The present system is especially useful as portable equipment in arid zones lacking in water, or in drilling through fissured formations causing excessive losses of drilling fluid, since it may be used for operations with a limited amount of

water which may be brought in a tank forming a part of the portable equipment.

Referring to Fig. 1, numeral 2 indicates a drill bit which may be of any desirable type or shape.

5 The bit is attached to the lower end of a string of drill pipe or tubing 10, which extends to the surface. Means for imparting to the string 10 a rotational motion, either manually or by power machinery, as, for example, through a rotary table, may be used in a manner well known in the art. A pump 24 is used to circulate a liquid such as water, brine or a suitable drilling fluid through the upper portion of the tubing 10, and is connected thereto by means of a conduit 28 provided with a valve 26, while a conduit 27 is used to return the liquid to the pump.

The bit 2 is affixed for axial motion within the enlarged lower cylindrical member 6 of the tubing 10, which tubing member 6 is provided with a bottom flange 4. The bit 2 has a cylindrical portion 8 provided at its upper end with a top flange 8a, adapted to fit slidably within the cylindrical member 6. A powerful spring 3 is wound around the cylindrical portion 8 of the bit, and is held between the flanges 8a and 4, whereby the motion of the bit with regard to the tubing string is limited, and the bit is normally held in a raised position with regard to said tubing string. Openings 6a are provided to prevent any liquid leaking past flanges 4 and 8a into the housing of the spring 3 from exerting any hydraulic effect opposing the compression of said spring.

35 The bit 2 may be provided with a passage 1, through which the liquid circulating in the system of pump 24, conduits 27 and 28 and tubing 10 may be passed into the borehole. The passage 1 is, however, normally closed by a plug 60, or a valve shown in Fig. 3, to be described hereinbelow. The conduit 27, connecting the tubing string 10 to the low side of the pump 24 is provided, near said tubing, with a valve comprising a valve cage provided with perforations 63 and 64 for the flow of the liquid in the conduit 27 as indicated by the arrow.

40 45 The valve cage 62 contains a ball valve 61 made of rubber or other suitable resilient material. When the pressure differential generated by the liquid flow at the operating pump pressure reaches a predetermined value, the elastic ball valve 61 is flattened or deformed and pressed against the bottom and walls of the valve cage, thus stopping the flow of the liquid and causing a water-hammer effect as will be explained hereinbelow. The hardness and resiliency, and the size of the ball valve 61, are selected with consideration to the

working pressure at which it is desired to operate the pump 24 to give an operative closure time for the valve structure.

The tubing 10 is extended above the point of its connection with conduit 27 to a desired height in order to regulate the frequency of operation of the impact bit, and may be provided with an enlarged portion 65 comprising a flow equalizer to be described hereinbelow. The tubing 10 is provided at the top with a swivel or other suitable connection 66, whereby a liquid, originally held in a tank 68 and supplied therefrom to the pump 24 through a pipe 69, may be circulated in a closed circuit comprising pump 24, conduit 28, swivel 66, flow equalizer 65, tubing 10, and conduit 27 returning to the pump. The water-hammer pressures generated by the valve 61—62 are transmitted to the bit 2 through the liquid filling the tubing 10 therebetween, the plug or valve 60 normally preventing any escape and loss of the fluid to the borehole.

When said circulation of the liquid is established by starting the pump 24 and opening the valve 26, a certain pressure differential is created by the flow of the liquid through the relatively restricted orifices 63 and 64 between the space within tubing 10 upstream of said orifices, and the space in conduit 27 downstream of said orifice, said pressure differential being a function of the rate of flow in passages 10 and 63—64, respectively.

The resilient ball 61 is selected of a compression strength such that it will close suddenly the orifices 64 when this pressure differential reaches a value corresponding to a predetermined fluid velocity in tubing 10 delivered by the pump 24, for example, 20 ft. per second, the valve 62 being in general adapted to close in a time period smaller than $2 L/u$, wherein L is the length of the conduits between the flow equalizers 14 (to be described hereinbelow) and the valve 62, and u is the velocity of transmission of pressure waves in the liquid, which for water is in practice about 4200 feet per second.

It is known from hydraulics that when, under these circumstances, the flow of the circulation liquid is abruptly stopped by the closure of the valve 11, its kinetic energy is transformed into static pressure energy. The high pressure which is thus generated, and which is additional to the working pressure developed by the pump, produces the so-called water-hammer effect, and may be expressed by the following formula derived from the equation of conservation of energy:

$$P = \frac{v u i c}{g}$$

wherein P is the maximum additional pressure produced by the closure of the valve 11, v is the velocity of liquid in the tubing, u is the velocity of transmission of pressure waves in the liquid, w is the weight of a unit volume of the liquid, and g is the gravitational acceleration constant.

When P and w are in pounds, and v and u in feet per second, the above formula becomes $P=63v$, or, taking into consideration the elasticity of the water and of the tubing, as well as various losses, about 600 to 2000 lbs. per sq. inch for the device of the present invention at working pump pressures of from about 60 to 100 lbs. per sq. inch.

These high additional pressures act to compress the spring 3 and to impact the bit 2

sharply against the formation to be drilled. Since, however, a water-hammer cycle consists of a high pressure period followed by a sub-normal pressure period, both the spring 3 and the valve ball 61 expand again during this latter period, thereby returning the bit 2 to its original position and opening the valve 62, after which the cycle is repeated.

While the bit is being reciprocated against the formation, the drill string may be caused to rotate by any desired means, whereby the cutting blade or blades of the bit are rotatably displaced with regard to the formation (substantially only during periods between successive impacts), and a better rate of penetration may be obtained.

As shown in Fig. 1, the drill pipe or tubing 10 is provided at any desired level above the conduit 27 with a plurality of annular internal funnel-shaped members 14, which may be attached, by welding or in any other suitable manner, to one or more of the tubing stands forming the drill string. The members 14 constitute an internal flow equalizer for the liquid circulating in the tubing, the air entrapped between the tubing walls and said funnel-shaped members serving to form a series of air chambers, as shown at 15. It is known that air chambers are very effective as shock absorbers for water-hammer pressures in that part of the equipment which lies between an air chamber and the point of flow origin, without affecting said pressures in that part of the equipment which lies between the air chamber and the point of flow closure. The flow equalizers 14 are, therefore, desirable for protecting the surface equipment, in permitting the pump to work smoothly and therefore raising its efficiency, and in controlling the frequency of the water-hammer cycles by limiting the amount of liquid which is accelerated. If desired, the diameter of the tubing stands comprising the internal flow equalizers 14 may be enlarged as shown at 65, so that the flow capacity of said stands may remain equal to that of the unobstructed stands. For purposes of control, the length of the tubing connected between flow equalizers and the bit may be varied, whereby the frequency of impacts is varied. In general, the frequency of impacts is a function of several factors. Thus, the cycle of each impact may be divided into three parts: first, the time necessary to accelerate the fluid in tubing 10 to the velocity at which the valve 62 will close; second, the time during which the high pressure prevails on the bit and said valve remain closed; and third, the time necessary for the spring 3 to force the bit back to its normal position, driving the water which collected in the bit chamber up into the flow equalizer. The first period depends mainly on the pressure which the pump 24 can maintain in the flow equalizer, the amount of water between the internal and the external flow equalizers which has to be accelerated, the velocity to which it has to be accelerated before the valve 62 closes; and, finally, upon the size of orifices 63—64. The second period is short, and is equal to the distance between the internal flow equalizer and valve 11 divided by the velocity of the elastic wave in the fluid. The third period may be given a desired small value by selecting a powerful spring 3. During the latter two time periods, the pump supplies the flow equalizers with fluid while increasing the pressure therein. This fluid is forced out again where needed during the acceleration period of the cycle. A suitable

operating frequency for the present system is, for example, 15 cycles per second.

When the present system is operated for protracted periods of time and at high frequency, the air in the air-cushion spaces 15 may become dissolved in the water which is constantly and violently agitated in contact therewith, whereby the effectiveness of these flow equalizers may be impaired.

It may, therefore, be sometimes desirable to replace the flow equalizers 14 by those shown in Fig. 2.

Fig. 2 shows an internal flow equalizer similar in principle to that of Fig. 1. Two stands of the tubing 10 are connected by means of a joint 51 having a relatively enlarged diameter. Affixed within the joint 51 is a cylindrical resilient sleeve 53 of a diameter substantially equal to the inside diameter of the tubing 10, whereby an annular air chamber 55 is formed between the sleeve 53 and the member 51. Water-hammer pressure surges within the tubing 10 distend the sleeve 53 to a position shown on the left-hand side of the drawing, whereby the same shock-absorbing effect is obtained as described with regard to the device of Fig. 1.

As stated above, the member 60 may be either a blind plug or a valve closing the passage 1 throughout the periods of hammer-drilling. A special arrangement of the valve 60, which permits said valve to open when desired to permit liquid circulation through the tubing or drill pipe 10, passage 1, and up the borehole in order to flush out the cuttings and debris accumulated during the hammering or drilling period, is shown in Fig. 3.

This valve comprises, within the tubing member 6, a housing 80, which may be of cylindrical shape and is screwed or attached to the bit 2 in a manner similar to that of the plug 60. The space within the housing 80 has a portion 87 in communication with the fluid within the tubing 10-6 by means of passages 81, and a portion 82 separated therefrom by means of fluid-tight flexible diaphragms 83 and 84, made of a resilient material such as rubber, the pressure-responsive area of diaphragm 83 being greater than that of diaphragm 84. A piston 85 is adapted to move within the housing 80 between said diaphragms. The piston 85 has attached thereto a stem 86, which passes through the diaphragm 84 and is attached thereto in fluid-tight manner, for example, by means of flanges 86a. The stem 86 terminates with a valve-head 88, which is adapted to close the passage 1 when the piston 85 is in its lowermost position. A spring 89 is provided to urge the piston 85 upwards. The space above the piston 85 is divided into two portions by a partition 91, said portions being in communication with each other by means of a small orifice or tube 90.

The space between the diaphragms 83 and 84 is filled with a suitable liquid, such as glycerine, water, etc., leaving preferably an air space shown at 92.

The effective pressure areas of diaphragms 83 and 84 and the force of the spring 89 are selected so that at normal working pressures of the pump, the effect of the pressure of the fluid in tubing 10 on the diaphragm 83 is able to overcome the pressure on the diaphragm 84 and the force of the spring 89. An equalization flow takes place through orifice 90 from the space above the partition 91 to the space below said partition, and forces the piston 85 downwards,

thus closing the passage 1. Since the orifice 90 allows only a slow equalization of pressure, a substantially constant pressure, which may be called the average pressure, prevails in space 92 during a hammering period, and maintains the passage 1 closed.

When, however, it is desired to flush out the cuttings accumulating in the borehole, the operator shuts off the pump 24, or otherwise allows the pressure in tubing 10 to fall below a predetermined value, whereupon the spring 89 overcomes the pressure-differential effect of the diaphragms 83 and 84, and raises the piston 85, thus permitting the fluid to pass through tubing 10 and 6 and passages 81 and 1 to the borehole. Considerable economies in operating fluid are thus realized by permitting fluid to circulate only through flushing periods, and shutting it off during hammering or drilling periods. In an embodiment of the present invention successfully used in the field, drilling was carried out with average pressures of from 70 to 100 lbs. per square inch, and flushing with average pressures of about 40 lbs. per square inch.

It is understood that the valve shown by numerals 61 and 62 in Fig. 1 is not confined to the particular structures shown in these figures, but embraces any structure wherein a liquid flow in a conduit system is abruptly stopped by resilient valve means in said conduit system, which is caused to close in a suitably short time period at a predetermined pressure differential created by said flow, thereby generating high pressure water-hammer effects.

I claim as my invention:

1. A hydraulic drilling system comprising a drill string, a drill bit normally sealing the lower end of said string and adapted for limited axial motion with regard thereto, spring means between said bit and said string regulating said motion, means for circulating a liquid in a closed hydraulic circuit, said means comprising said string, a pump, a first conduit in communication between the low side of said pump and said string, and a second conduit in communication between the high side of said pump and said string at a point spaced from said first conduit, and water-hammer means to reciprocate said bit with regard to said spring, said means comprising a restricted passage in said first conduit and normally open resilient valve means in said passage responsive to a predetermined flow pressure differential across said passage for suddenly closing said passage.

2. A hydraulic drilling system comprising a drill string, a drill bit normally sealing the lower end of said string and adapted for limited axial motion with regard thereto, spring means between said bit and said string regulating said motion, means for circulating a liquid in a closed hydraulic circuit, said means comprising said string, a pump, a first conduit in communication between the low side of said pump and said string, and a second conduit in communication between the high side of said pump and said string at a point spaced from said first conduit, water-hammer means to reciprocate said bit with regard to said spring, said means comprising a restricted passage in said first conduit and normally open resilient valve means in said passage responsive to a predetermined flow pressure differential across said passage for suddenly closing said passage, a fluid passage through the bit, valve means normally closing said passage, and valve control means responsive to a substantial pump pressure drop for opening said valve.

3. A hydraulic drilling system comprising a drill string, a drill bit normally sealing the lower end of said string and adapted for limited axial motion with regard thereto, spring means between said bit and said string regulating said motion, means for circulating a liquid in a closed hydraulic circuit, said means comprising said string, a pump, a first conduit in communication between the low side of said pump and said string, and a second conduit in communication between the high side of said pump and said string at a point spaced from said first conduit, water-hammer means to reciprocate said bit with regard to said spring, said means comprising a restricted passage in said first conduit and normally open resilient valve means in said passage responsive to a predetermined flow pressure differential across said passage for suddenly closing said passage, and at least one air chamber opening to said drill string between said first and second conduit.

4. A hydraulic drilling system comprising a drill string, a drill bit normally sealing the lower end of said string and adapted for limited axial

motion with regard thereto, spring means between said bit and said string regulating said motion, means for circulating a liquid in a closed hydraulic circuit, said means comprising said string, a pump, a first conduit in communication between the low side of said pump and said string, a second conduit in communication between the high side of said pump and said string at a point spaced from said first conduit, water-hammer means to reciprocate said bit with regard to said spring, said means comprising a restricted passage in said first conduit and normally open resilient valve means in said passage responsive to a predetermined flow pressure differential across said passage for suddenly closing said passage, and at least one air chamber opening to said drill string between said first and second conduit, the liquid space of said chamber being in communication with the bore of said drill string, and the air space of said chamber being separated from the liquid space by a resilient diaphragm.

EUGEN MERTEN.
